A. ZUCKERMAN.
DEVICE FOR AFFIXING TIPS TO SHOE LACES.
APPLICATION FILED FEB. 12, 1920.

1,363,949.

Patented Dec. 28, 1920.

INVENTOR
Abraham Zuckerman,
BY
Wm H Campfield,
ATTORNEY.

UNITED STATES PATENT OFFICE.

ABRAHAM ZUCKERMAN, OF NEWARK, NEW JERSEY.

DEVICE FOR AFFIXING TIPS TO SHOE-LACES.

1,363,949.

Specification of Letters Patent. Patented Dec. 28, 1920.

Application filed February 12, 1920. Serial No. 358,312.

To all whom it may concern:

Be it known that I, ABRAHAM ZUCKERMAN, a citizen of Russia, and a resident of Newark, county of Essex, and State of New

5 Jersey, have invented certain new and useful Improvements in Devices for Affixing Tips to Shoe-Laces, of which the following is a specification.

This invention relates to a device for affixing the tips to shoe laces, especially those tips that are made of thin sheet metal and are squeezed around the shoe lace, being either supplied in flat shape or in the form of a U-shaped piece. This device is made 10 so that anyone can affix a tip to a shoe lace, and is also adapted to be made in the form of a pocket device and can thus be utilized by salesmen and the like for more securely fastening the tips on shoe laces or for installing new tips on new laces.

The invention further consists of a device to be utilized for first forming the strip of thin metal into U-shaped form so as to make it ready for the reception of the shoe lace.

25 The invention is illustrated in the accompanying drawing, in which Figure 1 is a perspective view of one form of my improved device. Fig. 2 is a side view of the device shown in Fig. 1, but with the jaws 30 closed and with the shoe lace having a tip affixed thereto, the free or forward end of each jaw being shown in section, and Fig. 3 is a detail view similar to that shown in Fig. 2, but illustrating only the forward ends of 35 the jaws and the shoe lace and illustrating a modified form of die.

The invention consists of means for squeezing a tip on a shoe lace, and in the form shown comprises the jaws 10 and 11, 40 which are connected together so that they can swing relative to each other, in the form shown, this being done by bending a strip of metal to form the jaws, the bent or looped portion 12 thus providing a connection that 45 provides for a spring action of the jaws.

The jaws are provided on their ends with suitable dies 13 and 14, one die, such as the die 14, having a recess 15, and the other die having a projection 16 which fits in the recess 15, the inner end of the recess 15 and the outer end 17 of the projection being formed so that when they are forced together they will cause a shoe lace tip to be turned over so as to embrace or encircle the 55 end of the shoe lace. In the form shown the bottom of the recess 15 and the part 17 of

the projection 16 are shown as being recessed in a curved form so as to cause a thin sheet metal tip to be bent like a cylinder after it has been squeezed between the dies. 60

The shoe lace 18 is placed in the recess 15 along with the tip 19, these tips being formed so that they are U-shaped in cross-section, and the U-shaped piece is placed in the recess 15, then the shoe lace 18, being inside of the tip, is in a position to have the tip affixed thereto. This is done by squeezing the jaws 10 and 11 together, the free upper ends of the U-shaped piece then being engaged by the part 17, and are pressed down and squeezed so as to tightly embrace 70 the end of the lace.

If desired, one or both of the ends of the dies can be provided with projections 20 which cause an excess pressure on that part 75 of the tip engaged by such projection to press that part of the tip harder and thus embed it slightly in the shoe lace, so as to prevent the projection of any edge to be caught to tear the tip from the lace. This 80 is desirable because many tips are stripped from shoe laces when the shoe laces are being withdrawn or pulled out of the eye in the shoe in the act of loosening the shoe.

For the purpose of applying pressure to 85 force the jaws together I illustrate a lever 21, which is provided with a nose 22 and its inner end is pivoted, as at 23, by means of a pin 24 or by other suitable means, to the ears 25 of a yoke 26. The yoke is preferably 90 fastened to one of the jaws, such as the jaw 11 by a rivet 27, this preventing the separation of the parts. It will be evident that when the lever 21 is pulled down, the nose 22, engaging the outside of the jaw 10, forces 95 the jaw 10 toward the jaw 11 and thus causes an engagement of the jaws.

To hold the lever down in its closed position to permit continued pressure to be applied if desired, and also to hold the lever 100 21 out of the way if, in case of a small device, it is a pocket device, the lever is provided with a spring lip 28, which is disposed so that it is adapted to snap over the end 12 of the jaws and to be held in closed position, as shown in Fig. 2, by the spring action of the parts, and only released by pressing with the fingers on the extension 29 of the lever. 105

In case the tips for the shoe laces are supplied in the shape of small rectangular pieces of sheet metal, such pieces can be laid 110

over the recess 15 of the die 14 and then the dies swung together to cause the flat piece to be formed into a U-shaped piece, and then when the shoe lace is placed in this U-shaped piece and the jaws are again squeezed together, the two upwardly extending arms of the U-shaped or semi-cylindrical piece are forced inward, as above described, to closely embrace the shoe lace.

10 It will be evident that slight modifications can be made without departing from the scope of my invention.

I claim:

1. A device for affixing tips to shoe laces comprising a pair of jaws having a spring action to force them apart, dies on the ends of the jaws, the engaging faces of the dies being formed so as to squeeze a tip around a shoe lace, a yoke secured to one jaw and extending to the outside of the other jaw, a lever pivoted to said outside end of the yoke and having a nose thereon to engage the rear face of a jaw so that when the lever is swung the jaws are forced together, and a spring lip on the lever adapted to engage the ends of the jaws and adapted to be

snapped thereover so as to hold the lever in its closed position.

2. A device for affixing tips to shoe laces comprising a pair of jaws having a spring action to force them apart, dies on the ends of the jaws, the engaging faces of the dies being formed so as to squeeze a tip around a shoe lace, a yoke secured to one jaw and extending to the outside of the other jaw, a lever pivoted to said outside end of the yoke and having a nose thereon to engage the rear face of a jaw so that when the lever is swung the jaws are forced together, and a spring lip on the lever adapted to engage the ends of the jaws and adapted to be

snapped thereover so as to hold the lever in its closed position, the dies having one end of their abutting faces engaging the shoe lace tip projected so as to subject the part of the tip engaged thereby to a pressure in excess of the pressure applied to the remainder of the tip.

In testimony that I claim the foregoing, I have hereto set my hand, this 11th day of February, 1920.

ABRAHAM ZUCKERMAN.
